US00D374676S

United States Patent [19]

Brickner, Jr. et al.

[11] Patent Number: Des. 374,676

[45] Date of Patent: **Oct. 15, 1996

[54] SCROLL SAW

[75] Inventors: Louis C. Brickner, Jr.; Barry D. Wixey, both of Pittsburgh, Pa.

[73] Assignee: Delta International Machinery Corp., Pittsburgh, Pa.

[**] Term: 14 Years

[21] Appl. No.: 44,163

[22] Filed: Sep. 19, 1995

[52] U.S. Cl. D15/133

[58] Field of Search D15/133; 83/662, 83/669.21, 782-786

[57] CLAIM

The ornamental design for a scroll saw, as shown and described.

DESCRIPTION

FIG. 1 is a perspective view from the right and above the scroll saw of the present invention;

FIG. 2 is a perspective view from the left and below the scroll saw of FIG. 1;

FIG. 3 is a front elevational view of the scroll saw of FIG. 1;

FIG. 4 is a rear elevational view of the scroll saw of FIG. 1; FIG. 5 is a left side elevational view of the scroll saw of FIG. 1;

FIG. 6 is a right side elevational view of the scroll saw of FIG. 1;

FIG. 7 is a top view of the scroll saw of FIG. 1;

FIG. 8 is a bottom view of the scroll saw of FIG. 1;

FIG. 9 is a front elevational view of the scroll saw of FIG. 1 without a stand portion;

FIG. 10 is a rear elevational view of the scroll saw of FIG. 9;

FIG. 11 is a left side elevational view of the scroll saw of FIG. 9;

FIG. 12 is a right side elevational view of the scroll saw of FIG. 9;

FIG. 13 is a top view of the scroll saw of FIG. 9; and,

FIG. 14 is a bottom view of the scroll saw of FIG. 9.
